FIG. 1

FIG. 2

FIG. 3

FIG. 5

FIG. 1 is a top front perspective view of a portable beverage dispenser showing my new design.

FIG. 2 is a front elevational view thereof.

FIG. 3 is a rear elevational view thereof.

FIG. 4 is a side elevational view thereof.

FIG. 5 is a plan view thereof.

FIG. 6 is a bottom plan view thereof.

The side of the dispenser not shown in FIG. 1 is identical to the side shown.

The dominant feature of my design resides in the enclosure apart from the discharging spouts and bottle.

I claim:

The ornamental design for a portable beverage dispenser, substantially as shown and described.
